ELIHU HOSFORD, OF CHICAGO, ILLINOIS.

Letters Patent No. 86,072, dated January 19, 1869.

IMPROVEMENT IN BASE-BURNING STOVES.

The Schedule referred to in these Letters Patent and making part of the same.

To all whom it may concern:

Be it known that I, ELIHU HOSFORD, of Chicago, in the county of Cook, and in the State of Illinois, have invented an Improvement in Base-Burning Stoves; and do hereby declare that the following is a full, clear, and exact description thereof, reference being had to the accompanying drawing, making a part of this specification, in which—

Figure 1 is a vertical central section on the line xx of fig. 2.

Figure 2 is a horizontal cross-section on the line yy of fig. 1.

Letters of like name and kind refer to like parts in each of the figures.

My invention relates to heating-stoves in which the downward draught is employed; and

It consists in providing suitable openings through the sides of the combustion-chamber and ash-pit, below the grate, and covering said openings with mica, for the purpose of illuminating a room by means of the burning gas.

In the annexed drawing—

A represents the cylinder;

B, the combustion-chamber and ash-pit; and

C C, the hollow columns or flues for connecting said combustion-chamber with the hot-air chamber and smoke-flue.

All of these are similar in construction to and perform the same office as like parts in my coal-stove and cooking-range, for which Letters Patent, Nos. 76,455 and 80,484, were granted me.

D represents a conical grate, resting upon the upper end of a hollow column, E, (as in the before-mentioned cooking-range,) the lower end of which projects below

the bottom of the combustion-chamber, and forms a flue through which a current of cold air passes upward against the bottom of the grate, from whence it spreads outward and downward (as shown by the blue arrows) until it reaches the circumference of said grate, and meets the descending current of gas and smoke from the burning fuel, with which it unites, causing the most perfect combustion to take place, and producing a brilliant sheet of flame.

To enable the process of combustion to be observed, and also to enable the light from the burning gas to be used for illuminating the room, a number of openings, covered with mica, F F, are provided in the sides of the combustion-chamber, and in the door to the same.

I am aware that the use of similar openings in the sides of a stove, above the grate, has long been known, and therefore is not new; but this is believed to be the only instance in which said openings have been made below the grate for such a purpose.

Having thus fully described the nature and merits of my invention,

What I claim as new, and desire to secure by Letters Patent, is—

The application of the openings F F to the base of a stove, below the grate, substantially as and for the purpose shown.

In testimony that I claim the foregoing, I have hereunto set my hand, this 4th day of January, 1869.

E. HOSFORD.
